(57) CLAIM

The ornamental design for a cleaning sheet, as shown and described.

DESCRIPTION

FIG. 1 is a perspective view of an embodiment of a cleaning sheet;

FIG. 2 is a top view of the cleaning sheet of FIG. 1;
FIG. 3 is a side view of the cleaning sheet of FIG. 1;
FIG. 4 is a further side view of the cleaning sheet of FIG. 1;
FIG. 5 is a front view of the cleaning sheet of FIG. 1;
FIG. 6 is a back view of the cleaning sheet of FIG. 1; and,
FIG. 7 is a bottom view of the cleaning sheet of FIG. 1.
The broken lines shown in the drawings are for illustrative purposes only and form no part of the claimed design.
